UNITED STATES PATENT OFFICE.

THOMAS D. COOK, OF COUNCIL BLUFFS, IOWA.

CAR-BRAKE.

1,295,829.

Specification of Letters Patent.

Patented Feb. 25, 1919.

Application filed June 13, 1918. Serial No. 239,828.

To all whom it may concern:

Be it known that I, THOMAS D. COOK, a citizen of the United States, residing at Council Bluffs, in the county of Pottawattamie and State of Iowa, have invented certain new and useful Improvements in Car-Brakes; and I do declare the following to be a full, clear, and exact description of the invention, such as will enable others skilled in the art to which it appertains to make and use the same.

This invention relates to car brakes, and it relates more particularly to an improved brake-shoe-hanger.

15 One of the objects of this invention is to increase the degree of safety and efficiency in devices of this kind;

Another object is to provide a device of 20 this character which will be quickly and easily adjusted to conform to the tread of the car wheel;

Another object is to provide a device of 25 this character which consists of few and simple parts and may, therefore, be manufactured at a low cost;

Another object is to provide a device of 30 this character which is strong, durable, compact, convenient and thoroughly practical.

Other objects and advantages may become 35 apparent to persons who read the following details of description in connection with the accompanying drawings, in which:

Figure 1 is an elevation of a car truck having my improved brake-hanger applied 40 thereto;

Fig. 2 is an enlarged side elevation of my improved brake-hanger and its adjuncts;

Fig. 3 is a view partly in vertical section and partly in side elevation;

45 Fig. 4 is a horizontal sectional view along the line 4—4 of Fig. 2; and

Fig. 5 is a perspective view of a brake-head employed with this improved hanger.

Referring to these drawings in detail, in 50 which similar reference characters correspond with similar parts throughout the several views; the car truck frame A, axle B, and wheels C, being of ordinary construction, are not described in detail. A pivotal element 6 extends from each side of the truck frame, and on each of these elements 6 is pivotally mounted a bar or hanger 7 which is formed with lateral extensions 8 between which is inserted one end of a lever 9. The extensions 8 and corresponding lever 9 are provided with apertures through which

a pivot 10 extends. Each lever 9 may be connected in any appropriate way to any appropriate operating means (not shown). The levers 9, therefore, constitute means for 60 operating the hangers 7 by swinging them on their axes toward and from the car wheels. The lower end of each hanger 7 is formed with an apertured lug 11 to which the opposite hanger 7 is pivotally connected 65 through the medium of a link 12 and pivots or bolts 13.

On each hanger 7 is pivotally connected a shoe-carrier or brake-head 14 which may be of ordinary construction as regards its connection with the shoe 15. However, this brake-head is formed with opposite parallel flanges 16 between which the adjacent hanger 7 extends, and each brake-head 14 is pivotally secured to the corresponding 75 hanger by means of a bolt or pivot 17.

In order that each brake-head may swing freely upon these pivots 17, between predetermined limits, and in order to definitely determine such limits, I provide an adjusting device for each brake-shoe. Each of these limiting and adjusting devices comprises a strap or yoke 18 which is apertured at its ends for the reception of rivets or bolts 19 by means of which it is pivotally 80 secured to the brake-head; each yoke 18 also being centrally apertured, and these central apertures being screw-threaded for the reception of the set-screws 20. A lock nut 21 may be provided for each of the screws 85 20 so that the said screws may be securely held in their adjusted positions. The inner end of each set-screw 20 normally rests against the adjacent side of the hanger 7 which supports it, and the contiguous 90 brake-head 14 is thereby held approximately in position to conform to the periphery of the wheel against which it exerts its braking effect. Moreover, each yoke 18 together with its corresponding brake-shoe forms an 95 opening through which the corresponding hanger 7 extends, and the size of this opening is smaller than the cross section of the hanger at a point directly above the pivot 17; and therefore, if the pivot or bolt 17 100 should become broken or dislocated, the yoke 18 would combine with the relatively large cross section through the extensions 8 so as to prevent the brake-shoe from falling on the track, thus preventing a probable wreck 110 or derailment of the car.

From the foregoing disclosure, it will be

seen that the hanger 7 effects the following useful functions, (1st), supporting the brake-head, (2nd), supporting the device 18 and coöperating therewith to adjust the 5 brake-head, (3rd), supporting the ends of the levers which actuate the brakes, and (4th), supporting the link 12 which connects the hangers 7 and holds them in frictional contact with the portions of wheel 10 treads adjacent to the wheel flanges.

Although I have described this embodiment of my invention very specifically, it is not intended to limit this invention to these exact details of construction and arrangement of parts, but I am entitled to make minor changes without departure from the inventive idea disclosed in the foregoing description and following claims.

What I claim as my invention is:

20 1. In a car-brake, a depending hanger having a lateral extension, a brake-head pivoted on said hanger and adapted to carry a brake-shoe, a yoke extending around said hanger and secured to said brake-head, and 25 an adjusting element coöperative with said yoke for adjusting said brake-head with

relation to said hanger, said yoke also being cooperative with said lateral extension to support said shoe in case of failure of the pivot that connects said brake-head to said 30 hanger.

2. In a car-brake, a depending hanger having a lateral extension, a brake-head pivoted on said hanger and adapted to carry a brake-shoe, a yoke extending around said 35 hanger and secured to said brake-head, an adjusting element coöperative with said yoke for adjusting said brake-head with relation to said hanger, and means pivotally connected to said lateral extension for actuating said hanger so as to effect the braking function, said yoke being above said lateral extension and adapted to coöperate therewith for stopping the brake-head in case of failure of its pivotal support. 40

In testimony whereof I have hereunto set my hand.

THOMAS D. COOK.
